UNITED STATES PATENT OFFICE

159,913

VEHICLE CAB

John G. Macdonald, Goderich, Ontario, Canada

Application April 8, 1949, Serial No. 1,872

Term of patent 14 years

(Cl. D14—27)

To all whom it may concern:

Be it known that I, John G. Macdonald, a subject of the King of Great Britain, and resident of the town of Goderich, county of Huron, Province of Ontario, in the Dominion of Canada, have invented a new, original, and ornamental Design for a Vehicle Cab, of which the following is a specification, reference being had to the accompanying drawings, forming part thereof.

In the drawings,

Figure 1 is a side elevational view of a vehicle cab showing my new design.

Figure 2 is a front elevational view and Figure 3 is a plan view the side of the cab not shown being similar to the side shown.

I claim:

The ornamental design for a vehicle cab, as shown and described.

JOHN G. MACDONALD.
